UNITED STATES PATENT OFFICE

JOSEPH H. THORNLEY, OF EVANSTON, ILLINOIS

PILE DRIVER

Application filed November 13, 1929. Serial No. 406,759.

The present invention relates to movable derrick structures most commonly embodied in the form of pile drivers, and is divisional in part of my copending application on 5 "foundations for buildings, bridges, and the like," Serial No. 149,285 filed November 19th, 1926. The present type of derrick structure has its most widespread field of use in pile drivers for driving wood, concrete and metallic piles and for general utility work in the sinking or formation of composite piles and cast-in-place concrete piles. However, such type of movable derrick structure may also be employed for performing other operations such as drilling wells, mechanically digging foundation holes, etc. For example, in my above mentioned copending application I have shown a derrick structure which is used to operate a mechanical digging device and a drilling bit for sinking foundation holes.

The specific derrick structure therein disclosed is in reality a pile driver with certain auxiliary devices mounted thereon, but it illustrates that the invention can be embodied in movable derrick structures for digging or drilling wells and like work. However, for brevity of description I shall hereinafter refer to the structure as a pile driver.

One of the fundamental objects of the invention is to increase the facility with which the structure can be maneuvered to bring the derrick over different points of operation on the ground. In the construction of foundations, piers and the like requiring the driving of a large number of piles or involving successive operations of driving different parts of composite piles, removing cores and casings, etc., it is usually necessary 35 to shift the pile driver frequently in a short space of time. The ease and rapidity with which the structure can be maneuvered becomes an item of considerable importance in determining the cost of the particular job. 40 For example, in shifting from one point on the site to another the concrete gang or other part of the crew is frequently idle, or if the shifting is particularly laborious it may be necessary to draw men from other work to 45 assist in the operation. Hence, it has been

one of my objects to provide an improved pile driver and method of moving the latter which will greatly reduce the time and labor heretofore involved in shifting one of these structures.

In this regard, one of the features of the invention resides in increasing the number of directions in which the structure can be moved. For example, in most prior pile drivers which were moved on rollers which are picked up at the rear of the driver and replaced ahead of the driver in the direction of travel it was practically impossible to move the device sidewise except by causing it to travel diagonally in one direction on these rollers and then move diagonally in the other direction until the device had been shifted laterally to the desired degree. According to the present invention the structure can be moved sidewise, endwise or diagonally on the ground sills, skid timbers or such other means as affords the working surface on which the pile driver operates.

One of the principal objects of the invention is to provide an improved pile driver structure characterized by the bed of the pile driver being movably mounted on a pair of rails, which rails constitute a part of the entire movable unit which can be thus moved sidewise, endwise or diagonally as above stated. The invention also embodies improved methods of moving the bed along the rails, and also of moving or shifting the rails on the ground sills. In addition to these movements of the pile driver bed relatively to the rails, and of the rails relatively to the ground sills, the platform on which the derrick structure is supported can be revolved about a turntable mounting on the bed. The invention greatly increases the mobility of the structure so that it can be moved into corners and other cramped locations on the site which were very difficult of access with the prior structures and methods of moving the same. Moreover, a flexibility of operation is afforded which practically avoids the possibility of one of the skid timbers or one of the rails of the pile driver blocking off a spot on which it is desired to drive a pile.

Another object of the invention is to pro-

55

100

vide an improved construction of pile driver which will be capable of exerting practically unlimited hoisting effort without danger of tipping over the pile driver. In pulling 5 cores and casings out of the ground it is frequently necessary to exert a great hoisting pull downwardly from the derrick leads and owing to the considerable overhang of these derrick leads beyond the turntable mounting of the platform on the bed there is created a considerable force tending to tip the driver. The present construction is interlocked to the two rails on which the driver travels, and thus in the normal use of the 10 structure such hoisting pull cannot possibly tip the driver.

Other objects concerned with the manner of extending the tackle rigging from the winding drums on the platform to the skid 20 timbers, rails and bed of the driver, and concerned with other structural features of the device, will be hereinafter pointed out in the following description of a preferred manner of practicing my invention. In the accompanying drawings illustrating the same:

Fig. 1 is a fragmentary side elevational view of the machine.

Fig. 2 is a plan view of the same with part of the derrick or tower shown in section, 30 this figure also illustrating in dotted lines one step of moving the machine sidewise.

Fig. 3 is a detail sectional view taken approximately on the plane of the line 3—3 of Fig. 1, illustrating one mounting of the bed 35 of the machine on its attached track rails.

Fig. 4 is a similar view illustrating another mounting of the machine bed on these rails.

Fig. 5 is a vertical sectional view through 40 the turntable axis of another embodiment of the invention, illustrating the manner in which the cables for maneuvering the unit are extended down through the bed of the machine.

Fig. 6 is a plan view showing how the 45 cables are extended through the upper platform.

Fig. 7 is a fragmentary view of the end of 50 one of the rails on which the bed moves, showing the sheave block mounted on such rail, and

Figure 8 is a diagrammatic plan view of the machine, illustrating one arrangement of the cable connections for effecting a shifting of 55 the bed along the rails, or for effecting the shifting of the rails longitudinally under the bed and relative to the ground sills;

Figure 9 is a similar view illustrating one 60 arrangement of the cable connections for effecting a movement of both the bed and rails laterally across the ground sills;

Figure 10 is a similar view illustrating one 65 arrangement of the cable connections and the relation of a cooperating reaction point for effecting movement of the bed and rails to a

diagonal position or laterally across the ground sills; and

Figure 11 is a view similar to Figure 10 showing the relation of the cable connections and reaction point reversed or alternated for effecting movement of the bed in a reversely diagonal direction from Figure 10, whereby through successive movements, as shown in Figures 10 and 11, the entire structure can be "walked" sidewise over the ground sills.

Referring first to the form of derrick rig illustrated in Figs. 1, 2 and 3, it will be seen that it comprises an upper platform 16, on which is erected the tower 17, the power plant 18 and the hoisting drum or other operating parts 19. This platform has a turntable mounting on a lower frame or bed 22, which in turn has roller support on two parallel rails 23, such rails constituting attached parts of the movable unit. As shown in Fig. 2, the entire unit is supported on heavy ground sills or timbers 24a, 24b, 24c, etc., laid on the ground at spaced points, such timbers serving as skidways on which the two rails 23, 23 can be slid either laterally or longitudinally.

Referring to Fig. 3, each of the skid timbers is "scabbed" or faced on its upper side with a plank 24' of oak which is nailed thereto and which has its upper surface coated with grease.

The two parallel rails 23 extend transversely of the skid timbers so as to be supported thereon, such rails being preferably constructed as heavy H-beam sections (Fig. 3), although these rails might also be constructed of heavy timbers.

The undersides of these rails are likewise "scabbed" or faced with sections of oak plank 100 ing 23' which are suitably secured thereto and which are also greased. The transverse sliding motion of the two rails 23, 23 across the ground sills affords a lateral adjustment of the machine.

As an alternative arrangement, the ground sills 24a, 24b and 24c may also consist of I-beams or H-beams with the metallic upper surfaces thereof contacting directly with the metallic lower surfaces of the rails 23, both of these contacting surfaces being greased.

One of the longitudinal adjusting movements of the machine is obtained by arranging the bed or frame to move lengthwise of the rails 23, preferably rolling on sets of rollers 25 disposed at each end of the frame and bearing on the upper flanges 26 of the rails.

These rollers are boxed in between pairs of Z-shaped bars 27 which are bolted to the under side of the frame. The rollers have reduced journal ends 25' which have bearing support in holes in the vertical web portions of the Z-bars, or in bearing sockets or blocks which may be mounted on the bars to receive these journal ends.

The lower flanges 28 of the Z-bars extend under the upper horizontal flanges of the rails, thereby affording a hooked or embracing en-

70

130

gagement between the bed and the rails whereby upward or lateral separation of the bed from the rails is prevented. As will hereinafter appear, this embracing engagement 5 between the Z-bars 27 and the rails 25 prevents any possibility of the platform or bed of the machine tipping forwardly relatively to the rails under heavy hoisting stresses, which stresses would follow from pulling a 10 casing, core or pile out of the ground.

The platform 16 has any suitable turntable 15 mounting on the bed or frame 22, such turntable mounting comprising, for example, a series of rollers 29 tracking between upper and lower circular rails 31 and 32 secured respectively to the platform and to the frame.

A central king bolt 33 passes down from the platform through a suitable bearing secured to the frame bed, and this king bolt 20 may have a collar or nuts engaging thereon below the central bearing to prevent upward movement of this king bolt relative to the bearing in any tipping tendency of the platform.

Any suitable arrangement of segment, gear and pinion may be employed for rotating the platform 16 on this turntable mounting through power operating mechanism, or 30 cable means may be employed for swinging the platform.

By virtue of the foregoing construction, the machine has swinging movement around the turntable mounting, lateral movement 35 across the skid timbers 24a, 24b, etc., and longitudinal movement along the parallel rails 23. The lateral movement of the machine across the skid timbers is effected by taking a hitch to the bed 22 or to one of the 40 side rails 23 and pulling the machine laterally through an arrangement of tackle connected to any fixed point located to one side of the machine. The cable connections indicated at 35 in Fig. 2 are representative of 45 such tackle connections for sliding the machine. The power for operating this tackle may be derived from the cable drum or winch 19 which is mounted on the platform 16, and in this lateral movement both rails 23, 23 of 50 course move with the bed and platform as a result of the Z-shaped bars 27 embracing the upper flanges of these rails, the latter rails sliding readily over the skid timbers by reason of their greased contacting surfaces.

55 When the desired lateral movement extends beyond the ends of the timbers 24, additional timbers indicated in Fig. 2 are laid along side the first timbers in overlapping relation so that the movement of the machine may be 60 continued on this second set of timbers. A wide range of lateral movement is also available by pivotally swinging the bed and rails. The dotted line position of the rails in Fig. 2 illustrates this lateral swinging movement, 65 such being obtained by blocking the rails at

one end against movement and swinging the other ends of the rails through a tackle hitch as above described. The longitudinal movement of the bed 22 and platform 16 along the rails 23 may be similarly effected through a 70 tackle hitch extended to any fixed point adjacent the ends of the rails; or the bed or platform can be jacked along the rails. If a power drive is desired for movement in this direction, such may be obtained by providing toothed racks on the rails in which engage pinions carried by the bed 22 and arranged to be driven from any suitable source of power carried by the machine. When the bed approaches the ends of the rails in the progressive movement of the machine along the line of pile sinking operations, the rails slide forwardly under the bed to continue the track structure in the desired direction of travel. This operation is effected by blocking the bed 80 to any stationary point, such as to one of the skid timbers 24 and thereafter applying sliding effort to the rails to cause them to slide endwise across the skid timbers and relative to the bed.

For example, assuming that the bed has been rolled to the right in Fig. 2 so that it is approaching the right hand ends of the rails, and it is desired to continue the pile sinking 85 operations in this direction, the first step is to block the bed against movement to the left, as by interposing a suitable block or timber between the central skid timber 24b and any suitable abutment point on the underside of the bed. Thereupon cables 37 are extended from the winch or winding drum 19 out over sheaves 38 at the right hand end of the platform, from whence they are doubled backwardly under the platform for connection to the left hand ends of the rails through hooks or any other suitable attaching devices 39. It will be evident that as the cables 37 are wound upon the drums 19 the rails 23 will be caused to slide longitudinally to the right by reason of the inability of the bed 22 to move to the left. Thus, the rails may be slid progressively across the tops of successive skid timbers laid one after another like the ties in a road bed. By properly timing the shifting 100 movements of the rails 23 with the progressive movement of the machine, the latter may be moved along the pile driving line by the use of only three skid timbers 24a, 24b and 24c, the rearmost timber being removed and placed in front in each shifting movement as 105 the rails are slid forwardly, the weight of the machine being carried during the greater part of the time on two of these skid timbers. Obviously, travel in the opposite direction is a mere reversal of these steps. The previously 110 described endwise movement of the bed along the rails 23, 23 may be effected by not blocking the bed and extending the cables 37 to those ends of the rails in the direction in which it is desired to have the bed moved. It will be 115

evident that if the bed is free to move a winding tension exerted through these cables will cause the same to move along the rails.

As before described, owing to the fact that the Z-bars 27 hook under the flanges 28 of the rails, there is no possibility of the bed tipping downwardly or forwardly at the front end relative to the rails. Thus any tendency for the tower 17 and platform 16 to tip forwardly under the stress of a heavy hoisting load would also require the tipping of the rails 23, which obviously would be impossible with the rails extending forwardly beyond the end of the machine and having a point of support beyond the vertical line of the tipping load. There is little tendency to cause the tower and platform to tip laterally, but any such tipping tendency is resisted by the weight of one of the rails 23, which is very heavy and which would have to be lifted in such lateral tipping of the machine. Thus, stability of the relatively high tower or derrick 17 is assured at all times, even under the relatively heavy loads imposed in the operations of driving piles, lowering structural steel columns, pulling casing sections and piles, etc.

The pivotal turntable movement of the platform 16 relative to the bed 22 also enables the tower to be swung to either side or to the opposite end of the bed. This enables pile driving, digging and drilling operations to be carried on at either side of the machine or at either end thereof, which is of advantage for working into and out of corners and up into close proximity to other structures. The several adjustments and movements just described produce a machine having great mobility for maneuvering quickly to different points on the site. The machine can be easily dismantled for transporting from one building location or zone of operations to another. The tower, which can be readily knocked down and reerected, comprises in the main two vertical I-beams 17' forming the open front of the tower and serving as guide leads between which the pile driving, drilling and hoisting operations are supported and guided.

Fig. 4 illustrates a modified construction generally similar to Fig. 3 except that the rollers 25 are omitted and the bed 22 slides directly on the upper flange 26 of each rail 23. The bed is interlocked against tipping relatively to each rail by plates 42 which are secured to the underside of the bed and which have offset portions 42' engaging under the flanges 26 of the beam or rail 23. These plate members are preferably secured to the bed adjacent to the front and rear ends thereof, and may also be secured to the intermediate portion of the bed.

In Figs. 5 and 6, I have illustrated an embodiment having improved guide means arranged in close proximity to the turntable

axis of the platform and through which guide means the cable or cables can be extended down under the bed for leading to their points of hitch on the rails 23 or to stationary points of anchorage. This guide means comprises a central vertical passageway 44 in the platform 16 and a passageway 44' in the bed 22, aligning with the passageway 44. These passageways or openings are coaxial with the vertical king bolt 33' which ties the platform 16 and bed together and which defines the center of rotation of the platform on the bed. The platform may have turntable support on the bed by the arrangement of rollers 29 and rails 31 and 32 described of Fig. 1, or the main weight may be borne on inner main bearing surfaces 45 and 46, with the outer rails or surfaces 31' and 32' serving primarily to maintain stability. The upper end of the king bolt 33' is secured to a bracket structure 47 which is fastened to the platform 16 and the lower end of said bolt is secured to a plate or bracket structure 48 secured in turn to the bed 22, but spaced downwardly from the bottom thereof to provide clearance for two lower sheaves 49. Each of these is supported between spaced arms 51 extending from sleeve brackets 52 which are swiveled on the king bolt 33' so that the sheaves can swivel to practically any horizontal position about the axis of the king bolt.

A shoulder or collar 53 on the king bolt prevents the sleeve portions 52 of these swiveling brackets from moving upwardly along the bolt under the tension of the cables passing around the sheaves. Two upper sheaves 55 have bearing support in the upper bracket structure 47 on opposite sides of the king bolt 33' and with the grooves of said sheaves extending in a direction to lead the cables, designated 56, to the winding drums or winches 19, of which there are preferably two, one for each cable. By virtue of this arrangement of the upper and lower sheaves with the cables extending downwardly on opposite sides of the king bolt 33', the cables will always be maintained in spaced relation to each other and hence will not chafe and wear each other such as would be the case if the cables were allowed to contact. It will be noted that this spaced relation is maintained no matter how far the turn table or platform 16 is rotated in either direction, the cables merely wrapping around the king bolt in spaced relation. Similarly in the horizontal swiveling movement of the lower sheaves 49 the cables will remain in spaced relation, such horizontal swiveling movement maintaining each individual sheave in the direct line of the pull exerted through its cable irrespective of the point of attachment of the outer end of this cable. The king bolt 33' connects the platform and bed together so that any tipping tendency ef-

fective on the platform is transmitted to the bed which, as previously described, is positively held against tipping by its engagement with the upper flanges of the beams or rails 23.

As best shown in Fig. 7, sheaves 61 are mounted at both ends of each rail 23 around which the cables 56 can be reeved when it is desired to effect relative sliding movement between said rails and the bed 22 of the derrick structure. There are preferably two of these sheaves at each end of the rail for multiple reeving, both sheaves being pivoted on a pin 62 mounted between the top of the rail and an angle bracket 63. Also secured to the bed 22 at opposite ends thereof, and preferably directly above the rails 23, are sheaves 65. Either one or two of these sheaves may be mounted in a bracket 66 which is secured to the end of the bed. A suitable eye or anchoring hook 68 is secured to the outer end of each beam rail 23 and any similar eye or anchoring hook 69 is secured at each corner of the bed 22 in proximity to the adjacent sheave block 65. These eyes or hooks afford anchoring points for the dead ends of the cables in certain shifting operations, which I shall now describe.

With reference to Figs. 8, 9, 10 and 11 illustrating these shifting operations, I have designated one rail 23' and its associated set of sheaves as 61' and 65', to distinguish from the other rail and its associated set of sheaves. Fig. 8 illustrates one arrangement of cable reeving for effecting a relative endwise movement between the bed 22 and the rails 23, 23'.

One of the cables 56 is generally extended from under the bed outwardly to one end of one rail and the other cable 56' is extended from under the bed in the opposite direction to the opposite end of the other rail. While these cables might be hooked directly to the eyes 68' and 68 at these ends of the rails, it is preferable to obtain the added mechanical advantage available by reeving the cable 56' back and forth one or more times through the companion sheave blocks 61' and 65', and by a similar multiple reeving of the other cable 56 through the diagonally opposite, companion pair of sheave blocks 61 and 65. The cables may be dead ended either at the outer ends of the rails or at the corresponding corners of the bed 22. If it is desired to move the bed to the left the cable 56' is wound up on its winch and the cable 56 is paid out; and conversely, if it is desired to move the bed to the right the cable 56' is wound up and the other cable 56 paid out. It will of course be understood that, if desired, both cables may be connected with opposite ends of the same rail, for effecting such endwise movement of the bed.

When it is desired to slide the rails endwise under the bed the bed is preferably an-

chored in fixed relation, as by inserting chock blocks indicated in dotted lines at 71 between one end of the bed and any fixed point, such as against one of the ground sills. For example if it is desired to slide the rails 23, 23' to the right (Fig. 8), the one or more chock blocks 71 are inserted between the left hand end of the bed and one of the ground sills, as 24b, or the bed is otherwise held against movement toward the left. Thereupon, the cable 56' is wound in to slide the rail 23' to the right under the bed. Preferably, only one rail is slid at a time, the other rail then serving as an anchor guide for preventing slewing of the structure. After the rail 23' has been slid to the right as far as desired the left hand end of the other rail 23 is reeved up with a cable for sliding this rail to the right. The same cable 56' may be transposed to the pulleys 61 and 65 associated with this rail in the same relation as described in connection with the rail 23', or the other cable 56 may be reeved through these sheaves 61 and 65. In either case, tension exerted on such cable will cause the rail 23 to be slid under the bed to the right. At this time the other rail 23' is serving as an anchor guide. While I have described the separate sliding of the rails as being the preferred practice in most instances, it will be noted that the provision of the two cables 56 and 56' and the ability of the two lower pulleys 49, 49 to swivel to any position under the bed permits the two cables to be both extended to the left hand ends of the two rails for conjoint sliding movement of both rails. Sliding movement of the rails in the opposite direction is effected by blocking the other end of the bed and extending one or both cables to the opposite ends of the rails, as will be obvious from the foregoing.

The sliding movement of the rails can be continued indefinitely over successively laid ground sills 24a, 24b etc. by progressively moving the bed as the ends of the rails are brought up into proximity thereto. The foregoing is also true of the construction and arrangement illustrated in Figs. 1 and 2, as previously described.

Fig. 9 illustrates one method of moving the bed and rails laterally across the ground sills 24a, 24b, etc. The cables 56 and 56' are extended out around the sheaves on the ends of that rail at the side corresponding to the direction in which it is desired to move the unit. These cables may be dead ended at the ends of the ground sills, as illustrated in Fig. 2 or may be connected to any other fixed points of anchorage. Moreover, if greater mechanical advantage is desired the cables may be reeved around both sheaves of the blocks 62 and around one or more sheaves in sheave blocks connected to the fixed points of anchorage. The opposite ends of the rails may be shifted separately with a zig-zag motion across the ground sills by first winding

in on one cable and then winding in on the other; or both ends can be moved simultaneously by winding in on both cables simultaneously.

5 Figs. 10 and 11 illustrate other methods or steps in moving the structure to diagonal positions or laterally across the ground sills. For example, if it is desired to move the left hand ends of the rails in the direction 10 of the arrow *a* (Fig. 10) to a diagonal position, the cables 56 and 56' are reeved as shown and a chock block or stationary abutment 71' may, if desired, be arranged to bear the reaction pressure at one end of one of the 15 rails. Simultaneous winding in of both cables causes the rail 23 to be projected to the right and causes the rail 23' to be projected to the left. In both cases the rails slide under the bed and across the ground sills 20 24*a*—24*c*. A certain amount of friction is always inherent in such movement of the rails on the ground sills, and when the two rails are projected in opposite directions in this manner, since the rails are a finite distance apart and since the force required to 25 shift the rails is a couple acting against the platform 16 which is supported on the rails, an equal but opposite reaction, namely, a second couple, is set up and acts through the 30 platform 16 and rails 23 and 23' against the ground sills. This reaction force couple is indicated by the arrows *b* and *c* in Figure 10. The effect of this reaction is a rotative force 35 tending to swing the bed and rails in a counterclockwise direction. Thus the entire structure can be swiveled into a diagonal position on the ground sills. If the chock block or other stationary abutment 71' is employed to hold one end of the rails against slewing, 40 the other ends of the rails receive the entire rotative force for swinging in the opposite direction. By appropriately reeving the cables and locating the chock block the structure may be swung in either direction. Fig. 45 11, for example illustrates a position into which the structure may have been swung when rigged as shown in Fig. 10, but shows the cables through the diagonally opposite sheaves and with the chock block at the other 50 ends of the rails. When tension is now exerted on the cables the rail 23 will be projected to the left under the bed, and the rail 23' will be projected to the right under the bed, substantially in a reversal of the directions of motion described of Figure 10, whereby 55 the right hand ends of the rails will swing in the direction of the arrow *d* in Fig. 11. From any of the diagonal positions to which the structure may be moved, as 60 above described, the rails and bed can then be slid endwise in accordance with the method described of Fig. 8 so that the structure can be moved into corners or other cramped locations on the site along lines diagonal to the 65 previous lines of movement of the structure.

Moreover, if desired, by alternately reversing the cable connections and the location of the chock block 71' the bed and rails can be "walked" sidewise across the ground sills 24*a*—24*c* with a zig-zag motion. It will be 70 noted that in all of these operations described of Figs. 10 and 11 the forces are self-contained in the structure, i. e. there is no necessity of extending one of the cables to a stationary point of anchorage outside of the 75 structure.

Attention is directed to the fact that by extending the cables down through the platform and bed to the swiveling sheaves 49 the line of pull effective on the structure is at a very low point of the bed so that a very large force can be exerted through either cable without tipping the structure. Moreover, such arrangement results in there being practically no tendency to rotate the platform on the bed notwithstanding a large tension set up in the cable or cables. Of course the shifting operations may be performed from tackle connections reeved through pulleys mounted on the rotatable platform, as illustrated in Fig. 2, the conventional mechanism for rotating the platform on the bed having the capability of locking the platform against such rotation, but the construction shown in Figs. 5 and 6 has the advantage of substantially eliminating this rotative tendency. Furthermore, the latter arrangement may remain reeved at all times in the use of the apparatus, the rotation of the platform interfering in no way with the 85 tackle connections. 90

95 While I have shown what I regard to be the preferred manner of practicing my invention it will be understood that such is merely exemplary and that other practices and constructions may be adopted within the broader aspects of the invention. 100

I claim:

1. In a pile driver of the class described, the combination of a bed, a platform, a pivot connection between said bed and said platform permitting horizontal rotative movement of said platform on said bed, a derrick rising from said platform, cable winding means on said platform, a pair of rails materially longer than said bed and along which the bed is adapted to move, guide means for guiding relative movement between said rails and said bed in a direction longitudinally of the rails, said guide means positively preventing tilting of said bed relative to said rails, a plurality of skid timbers adapted to be supported on the ground, said pair of rails having slideable mounting on said timbers to be skidded endwise and side-wise thereon a cable adapted to be extended from said winding means to a point of anchorage for effecting movement of said bed on said rails or movement of said rails on said skid timbers, said rails having free slid- 110 115 120 125 130

ing mounting on said skid timbers so as to enable them to be skidded in any direction, endwise or sidewise, on said timbers, and said rails being capable of motion independently of each other in their endwise sliding movement, said platform having an opening therein in proximity to said pivotal connection for permitting said cable to be passed from said winding means down through said opening to the lower portion of the pile driver, and a pulley mounted on the lower portion of the pile driver substantially in line with said opening and having a horizontal swivelling movement for guiding the cable substantially horizontally to different points of anchorage.

2. In pile driving apparatus, a pile driver having a bed, a plurality of ground sills disposed in spaced relation on the ground, a pair of independently movable rails slidably supported on said sills for movement in a plurality of directions, said pile driver bed being movably carried upon said rails, means carried by the pile driver for shifting said rails and pile driver carried thereby bodily across said ground sills, and means carried by the pile driver for shifting the rails relative to the ground sills and to the pile driver, when the latter is held stationary with the weight of the pile driver imposed upon the rails.

3. In a pile driver movably mounted on a pair of spaced apart rails materially longer than said pile driver and supported on ground sills, the method of bodily maneuvering said pile driver and rails over the ground sills, which comprises shifting the rails longitudinally in opposite directions relative to the pile driver and the ground sills while the weight of the latter is imposed on said rails, thereby establishing a reaction couple acting to displace the pile driver and rails as a unit angularly on said ground sills.

4. The method of maneuvering a pile driver mounted for endwise movement on two substantially parallel rails, said rails being mounted for both endwise and sidewise movement on ground sills, which method comprises extending a cable from power means on the pile driver to one end of one of the rails and connecting said end therewith, extending a second cable from said power means to the opposite end of the other rail and connecting the end of said second cable therewith, establishing a point of anchorage for one end of said rails to prevent sidewise movement thereof along the sills in one direction, and creating tension in said cables to project at least one of said rails across said ground sills, the resultant friction serving to establish oppositely acting reaction forces in said rails, thereby creating a reaction couple effective to shift said pile driver and rails sidewise about said point of anchorage as a center.

5. The method of maneuvering a pile

driver mounted for endwise sliding movement on two substantially parallel rails, said rails being mounted for both endwise and sidewise movement on ground sills, which method comprises extending a cable from power means on the pile driver bed to one of said rails and connecting said cable therewith in such a manner that tension in the cable will tend to shift the rail under the pile driver, anchoring the pile driver bed against movement relatively to said ground sills, creating tension in said cable to cause said latter rail to be shifted endwise across said ground sills and under said bed, and performing these same operations on the other rail, then removing the anchoring for the bed and shifting the bed relative to both the rails and ground sills to bring the pile driver to a different position relative to the ground sills.

6. In a pile driver of the class described, the combination of a pile driver bed, a platform mounted thereon, cable winding means on said platform, a pair of independently movable rails along which said bed is adapted to move, guide means for guiding relative movement between said rails and said bed in a direction longitudinally of the rails, ground supporting sills on which said rails are supported for endwise and sidewise movement, said rails having free sliding mounting on said sills so as to enable them to be skidded in any direction, endwise or sidewise, on said sills, a cable adapted to be extended from said winding means to one end of one of the rails and connected therewith so as to shift the same in one direction relative to the bed and ground sills when tension is created in the cable, means establishing a point of anchorage for one end of said rails to prevent sidewise movement thereof along the sills, and a second cable adapted to be extended from said winding means to the opposite end of the other rail so as to shift the same in the opposite direction relative to the bed and ground sills, the friction due to the weight of the pile driver and the rails on the ground sills establishing a reaction couple when the rails are shifted in opposite directions acting to shift the pile driver and rails angularly on the ground sills about said anchorage means as a center.

In witness whereof, I hereunto subscribe my name this 9th day of November, 1929.
